UNITED STATES PATENT OFFICE.

ROBERT C. GLASSCO, OF ANDERSON, INDIANA.

FENCE-POST.

No. 852,555.

Specification of Letters Patent.

Patented May 7, 1907.

Application filed July 5, 1906. Serial No. 324,724.

To all whom it may concern:

Be it known that I, ROBERT C. GLASSCO, a citizen of the United States, residing at Anderson, in the county of Madison and State of Indiana, have invented new and useful Improvements in Fence-Posts, of which the following is a specification, reference being had to the accompanying drawings, forming a part thereof.

10 The purpose of this invention is to provide an improved fence post having a metallic base, or to provide a metallic base to which a post may be attached above ground: that is to say, the base may be provided for attachment thereto of any sort of upper portion desired.

The invention consists in the elements and features of construction shown and described and set out in the claims.

20 In the drawings:—Figure 1 is a perspective view of a fence post embodying this invention. Fig. 2 is a section at the line 2—2 on Fig. 1. Fig. 3 is a section at the line 3—3 on Fig. 1. Fig. 4 is a perspective view of one 25 of a pair of mutually bracing members which constitute the major portion of the under-ground extent of the post. Fig. 5 is a detail side elevation of the portion of the post appearing above the ground, including a wooden 30 upper member, showing its adaptation to have such upper member applied alternatively either erect or in the leading position illustrated in dotted line. Fig. 6 is a similar side elevation showing the fence above 35 ground laid flat without disconnection from the base. Fig. 7 is a detail vertical section of the upper end portion of the base and lower end portion of the above-ground or 40 wooden element, showing a modification in respect to the mode of attaching the two parts together.

The metal base shown in the drawings is intended to have secured to the portion which protrudes above ground a wooden portion 45 which does not reach the ground and is therefore saved from exposure to the rotting which is caused by alternate soaking and drying to which a wooden post sunk in the ground is exposed for a distance from the surface of 50 the ground; but the invention is not absolutely limited to the employment of a wooden upper element. The base to which the upper element is attached, whether the latter be wood or metal, comprises a rectangular 55 bar, 1, designed to protrude above the ground, and having its lower end embraced

by two channel-bars, 4, 4. These channel-bars are identical in form and dimensions, the width of the channel being greater than the width of the bar, 1, by substantially the 60 amount of one flange of the channel-bar, so that the two channel-bars being engaged with each other channel to channel, one flange of each channel-bar being within the channel of the other, the space remaining in 65 the channel is the width of the bar, 1, which is engaged between the two bars and in contact with one flange of one bar and the opposite flange of the other bar. The flanges, 5, 5, of these channel-bars are preferably tapered from the upper end to a point within a few inches of the opposite end, where the flange substantially disappears or becomes very narrow; and at this point the main web 70 of the channel-bar which beyond this point 75 is a flat bar only, without flanges, is bent outward at a slightly obtuse angle, forming a foot or lip, 6, so that with the two channel bars engaged, as described, at the upper end, and the foot pieces or lips, 6, in the same 80 plane, the channel-bars themselves diverge from the upper end toward the lower end, as seen in Fig. 1.

8 is an anchor-plate having two parallel slots, 9, through which the lips or feet, 6, of the channel-bars may be entered from the upper side of the plate, being engaged under the plate as the channel-bars are straightened upward in the process of hooking the lips through the slots; and the channel bars being brought together embracing at their upper ends the rectangular bar, 1, and said bar being secured in place between the channel-bars by a bolt, 10, the anchor-plate will be found rigidly secured to the lower ends of the 90 channel-bars without capacity for sliding on them, being of course stopped in one direction by the lip, 6, and being stopped in the other direction, not only by the flanges, 5, which, as described, extend down to the 100 point where the lips are formed, but also by the convergence of the two bars, 4, from the plate upward, which, even in the absence of the flanges, 5,—that is, even if they do not extend entirely down to the plate,—would 105 defeat the possibility of crowding the plate upward, because this could be effected only by bending the bars, 4, as they would be wedged apart by the crowding of the plate up between their converging inner faces; and 110 these bars are rendered by the flanges too stiff for such bending, and may, in any event,

be of material too stiff to be so bent except by very much greater force than would ever be operative on the post in the ground to produce any such movement of the plate.

5 In order that a section of a fence may be laid down flat upon the ground to drive over it, avoiding often the necessity of long detours or of breaking through the fence for the purpose of crossing it, I secure the upper 10 post-member, 12, to the bar, 1, by two bolts, of which the lower bolt, 13, is so near the ground that when said post member is turned about it as a pivot, it will lie practically flat on the ground. The second bolt, 15 13^a, is located near the upper end of the bar, 1. The apertures, 11 and 11^a, in the bar, 1, for receiving these bolts are elongated, the lower constituting a slot and the upper extending to the upper end of the bar and constituting a notch. When it is desired for any 20 purpose to lay a section of the fence flat, the two bolts being merely slackened, the upper post member may be lifted to carry the upper bolt out of the notch, 11, freeing the post 25 therefrom and leaving it merely pivoted on the lower bolt, 11^a, so that it may be swung over to horizontal position flat on the ground, as described. This feature of construction is often serviceable in preventing the 30 destruction of the fence by floods, for in anticipation of floods the upper bolts, 13, at the notches, 11, may be withdrawn, leaving all the upper post members pivoted on the lower bolts, so that the whole fence will be swept 35 flat by flood and will thus avoid being torn away by floating debris as would otherwise be the case.

For the purpose of preventing stock from 40 trampling on the lower wires or bars of the fence as they are liable to do when they crowd up to the fence, it is desirable that the fence be set in an inwardly leaning position, so that when the shoulders of the animals strike the upper bar or wire they will be too 45 far away from the lower bar to be liable to reach it with their feet in pawing the ground, and so avoid the danger of becoming entangled in the fence as well as the danger of tearing loose the lower bars or wires. In order 50 that the fence built with posts of the present invention may be set leaning if desired, I preferably make the slots, 11 and 11^a, in the bars, 1, for the bolts which secure the upper post member, 12, (usually made of 55 wood, as above stated,) a little out of vertical line, and the corresponding holes, 12^a, in the member, 12, at such position that said member when applied with one side toward the bar, projects vertically, but when applied 60 with the other side to the bar projects at an inclination due to the inclined direction of a line connecting the two slots, 11^a, and the correspondingly inclined direction of the line connecting the bolt holes, 12^a, with respect 65 to the longitudinal dimension of the post

member, 12. It will be seen that if the two holes, 11^a, are, for example, eight inches apart and are a half inch out of vertical line, the reversal of the post-member, 12, will give an inclination amounting to one inch in 70 eight inches of length so that a post four feet high will overhang twelve inches at the top.

The member, 1, of the post is provided on opposite sides with L-shaped stress-plates, 2, 2, one limb of the plate being bolted fast 75 against the side of the post member and the other projecting at right angles off from the side at one edge or corner of the post, the two stress-plates being oppositely placed so that their said members projecting off from the 80 post project thus at diagonally opposite corners of the post. Both plates may be secured by the same bolt, 3. These stress-plates serve to hold the post against lateral stress, resisting thus any tendency to displace the post in a plane at right angles to the plane of the wires, the wires themselves serving ordinarily to prevent displacement of the post in the plane in which they are stretched.

90 I claim:—

1. A fence post comprising an upright metal bar substantially rectangular in cross-section; an anchor-plate and two braces which are footed on the anchor-plate at a 95 distance apart and converged to opposite parallel sides of the rectangular bar, and bolted thereto engaging said bar between them.

2. A fence-post base comprising an upright bar, a horizontal anchor plate; a pair of channeled braces footed on the anchor plate and converged to opposite sides of the upright bar, and at their upper ends embracing the bar in their channels and secured to 105 the bar.

3. A fence-post comprising an upright bar, a horizontal anchor plate and a pair of channeled bar braces having their webs turned outwardly at the lower end to form lips or 110 feet, the anchor plate being slotted and the lips or feet of the braces being hooked through the slots and engaged on the under side of the plate, the bars being converged from their said engagement to the plate upwardly to the opposite sides of the upright 115 bar and secured thereto.

4. A fence post base comprising an upright bar, a slotted horizontal anchor plate; a pair of channel bar braces having their web at the 120 lower ends bent outward to form lips or feet hooked through the slots of the anchor plate and engaging thereunder, said braces being converged from the anchor plate upwardly and at their upper ends embracing the 125 upright bar in their channels and secured to said bar.

5. A fence-post base comprising an upright bar, an anchor plate and means for rigidly connecting the bar to the plate, and op- 130

positely projecting wings made rigid with the bar at the upper portion below the ground line.

6. A fence post comprising an upright element; an anchor plate; diverging braces rigidly connecting the bar to the plate, and oppositely projecting wings rigid with the bar at the upper portion thereof, below the ground line, extending in the direction in which the braces diverge.

7. A fence post comprising a metal base having an upper terminal bar protruding above the ground, and an upper member secured to said terminal bar, the bar having elongated bolt-holes or slots, the upper slot

extending to the upper end of the bar and constituting a notch therein, and bolts taking through said slots and engaging the upper member for securing it to the bar, adapted to be slackened to permit the upper bolt to be disengaged from the notch to allow the fence to be laid flat.

In testimony whereof, I have hereunto set my hand in Chicago, Illinois, this 28th day of June, A. D., 1906.
